CLAIM

We claim the ornamental design for the agricultural tillage pivoting gauge wheel, as shown and described.

DESCRIPTION

FIG. 1 is an upper right, perspective view of the agricultural tillage pivoting gauge wheel;

FIG. 2 is a right view of the agricultural tillage pivoting gauge wheel;

FIG. 3 is a left view of the agricultural tillage pivoting gauge wheel;

FIG. 4 is a front view of the agricultural tillage pivoting gauge wheel;

FIG. 5 is a rear view of agricultural tillage pivoting gauge wheel;

FIG. 6 is a top view of agricultural tillage pivoting gauge wheel; and,

FIG. 7 is a bottom view of agricultural tillage pivoting gauge wheel.

The broken line showing of environmental features is included for the purpose of illustrating non-claimed subject matter and forms no part of the claimed design.
